UNITED STATES PATENT OFFICE.

KIRTLAND C. GARDNER, OF CORAOPOLIS HEIGHTS, PENNSYLVANIA, ASSIGNOR TO
UNITED ENGINEERING AND FOUNDRY COMPANY, OF PITTSBURGH, PENNSYLVANIA, A CORPORATION OF PENNSYLVANIA.

COIL CARRIER.

Application filed February 21, 1923. Serial No. 620,541.

To all whom it may concern:

Be it known that I, KIRTLAND C. GARDNER, a citizen of the United States, residing at Coraopolis Heights, county of Allegheny, 5 and State of Pennsylvania, have invented a new and useful Improvement in Coil Carriers, of which the following is a full, clear, and exact description.

The present invention relates broadly to 10 supports, and more particularly to supports or coil carriers adapted to receive a plurality of coils of strip material, as formed in a rolling mill.

In certain mills, it is customary to coil 15 strip material as delivered by the last stand of rolls, and then store, ship, pickle, recoil or otherwise treat the coiled material. By the present invention there is provided an improved means for receiving the coils 20 either directly from a coiling device, or from any other source, and adapted to temporarily store the same until it is desired to transfer them to some other point.

In view of the comparatively limited 25 room available in most mills, it is desirable to have the carrier occupy as little room as possible, and at the same time to have a comparatively large capacity.

The foregoing and other objects are accomplished by the embodiment of the invention shown in the accompanying drawings for purposes of illustration only. It will be understood that the drawings do not limit the invention, as changes may obviously be made in the construction and operation disclosed without departing from the spirit of the invention or scope of my broader claims.

In the drawings:—

40 Figure 1 is a top plan view, partly broken away, illustrating a carrier constructed in accordance with the present invention,

Figure 2 is a vertical sectional view on the line II—II of Figure 1,

45 Figure 3 is a transverse sectional view, on an enlarged scale, through a portion of one of the coil supporting arms,

Figure 4 is a detail sectional view on the line IV—IV of Figure 3, and

50 Figure 5 is a sectional view on the line V—V of Figure 2.

In constructing a coil carrier in accordance with the present invention, there may be provided a suitable foundation 2 of any

desired material, and preferably formed 55 with a central opening 3. Mounted upon and secured in any customary manner to the foundation is a support 4 in the form of a tubular vertically extending standard. This standard is shaped to provide bearing portions 5 and 6 for cooperation with a sleeve 7.

Secured to the sleeve 7 are a plurality of 60 guides 8 forming opposed guide slots 9 adapted to detachably receive the curved 65 inner ends 10 of coil supporting arms 11. As clearly shown in Figure 2, the inner ends 70 10 of the coil arms are provided at their upper portions with inwardly extending lugs 12 adapted to overlie the upper end 75 of the sleeve 7 to limit the downward movement of the coil arms within the guide slots 9. At their lower portions, the inner ends 10 may be formed with a flange 13 projecting inwardly and adapted to abut against 80 the exterior of the sleeve 7. This construction permits the coil arms to be independently lifted upwardly and removed for repair or to permit the substitution of new arms, 85 as may be required.

In order that the coil arms 11, of which any desired number may be provided for a single standard, may be brought to the required operating position for loading or unloading the same, the sleeve 7 may be 90 provided with a ring gear 14 adapted to be driven by a pinion 15, either continuously or intermittently, as may be found preferable.

In order to prevent undue radiation of 95 heat upwardly from the coils C, some of which are indicated in chain lines in Figures 2 and 5, the entire carrier may be covered by a plate 16 held in the desired position by braces 17 secured thereto and extending downwardly within the standard 4 to which they may in turn be secured in any convenient manner.

Where the coil carrier is utilized for receiving hot coils directly from a coiling device, it is necessary to cool the supporting arms to prevent burning out or pitting thereof. This cooling may be accomplished by constructing each of the arms with a water chamber 18 adapted to receive water 100 through suitable passages 19, as clearly shown in Figures 3 and 4. These passages 105 may in turn be in communication with a

source 20 of cooling water, preferably located immediately below the cover 16 and kept supplied at all times through a pipe line 21. After filling the arms 11, the water is adapted to overflow therefrom through passages 22 into connections 23 discharging into the interior of the standard 4. This water so discharged may pass through the standard and foundation, from which it is withdrawn through a sewer connection 24.

At certain times during the use of the coil carrier, it may be desired to cool the coils to permit convenient handling thereof. In such cases, a suitable exhauster (not shown) may be connected to the chamber 3 within the foundation for continuously drawing air across the coils below the cover plate 16, and thence downwardly within the standard.

The advantages of the present invention arise from the provision of a coil carrier adapted to receive a plurality of coils, and either conserve the heat thereof or cool the same, as may be desired.

Further advantages arise from the provision of independently removable coil supporting arms, whereby they may be individually repaired or renewed, as found necessary.

I claim:

1. In a coil carrier, a fixed standard, a plurality of arms extending outwardly therefrom, means for rotating said arms, and means for cooling said arms, substantially as described.

2. In a coil carrier, a standard, a sleeve rotatably cooperating with said standard, a plurality of arms extending outwardly from said sleeve, and means for rotating said sleeve, substantially as described.

3. In a coil carrier, a standard, a sleeve rotatably cooperating with said standard, a plurality of arms extending outwardly

from said sleeve, and means for cooling said arms, substantially as described.

4. In a coil carrier, a fixed standard, a plurality of coil receiving arms detachably secured to said standard and extending outwardly therefrom, means for rotating said arms, and means for supplying cooling water continuously to each of said arms, substantially as described.

5. In a coil carrier, a standard, a sleeve rotatably cooperating with said standard, a plurality of guides carried by said sleeve, and coil supporting arms adapted to detachably cooperate with said guides, substantially as described.

6. In a coil carrier, a standard, a sleeve rotatably cooperating with said standard, means for rotating said sleeve, guides carried by said sleeve, and a plurality of coil receiving arms detachably supported by said guides, substantially as described.

7. In a coil carrier, a standard, a plurality of arms extending outwardly from said standard, a cover for said carrier, and means for inducing a circulation of air below said cover, substantially as described.

8. In a coil carrier, a plurality of radially extending coil receiving arms, means for supplying cooling water to each of said arms, a cover for said carrier, and means for inducing a circulation of air below said cover, substantially as described.

9. In a coil carrier, a plurality of radially extending coil receiving arms, means for bringing said arms successively to different positions, means for water cooling said arms, and means for inducing a blast of cooling air across the coils carried by said arms, substantially as described.

In testimony whereof I have hereunto set my hand.

KIRTLAND C. GARDNER.
